FIG. 1 is a top plan view of a game board showing my new design;

FIG. 2 is a side elevational view of the game board illustrated in FIG. 1;

FIG. 3 is a perspective view of the game board illustrated in FIG. 1; and

FIG. 4 is an end elevational view of the game board illustrated in FIG. 1.

My design comprises a generally planar structure formed of longitudinally extending, narrow, vertical laminae, the general outline being in the form of a pair of overlapped circles terminating in squared tabs at opposite ends thereof, the whole suggesting a base viol, the upper surface thereof being perforated in a pattern following the said general outline, all as shown.

This application is a continuation-in-part application of my prior copending application Serial No. D. 61,706, filed August 11, 1960, now abandoned.

I claim:

The ornamental design for a game board, substantially as shown and described.
